CLAIM

The ornamental design for a tape drive, as shown and described.

DESCRIPTION

FIG. 1 is a front left side perspective view of the tape drive showing our new design;

FIG. 2 is a front elevational view thereof;

FIG. 3 is a top plan view thereof;

FIG. 4 is a bottom plan view thereof;

FIG. 5 is a rear elevational view thereof;

FIG. 6 is a right side elevational view thereof;

FIG. 7 is a left side elevational view thereof;

FIG. 8 is a front elevational view of a second embodiment of our new design.

The undisclosed views of the second embodiment are identical to those of the first embodiment.

FIG. 2

FIG. 1

FIG. 3

FIG. 4

FIG. 8

FIG. 7
